SINGLE BLANK CLOTH BOARD END CAP

Walter A. Becker, High Point, and Carl P. Cato, Charlotte, N. C., assignors to Old Dominion Box Company, Lynchburg, Va., a corporation of Virginia

Application August 26, 1947, Serial No. 770,652

1 Claim. (Cl. 229—16)

1

This invention relates to a bolt board and more especially to a quickly attachable end piece to be placed over the end of the bolt board. Bolt boards were formerly made of wood but now are usually made by folding a sheet of corrugated paper to provide a bolt board on to which bolts of cloth are wound. This usually presents an uneven and unfinished end portion at each end of the bolt board and makes an unsightly appearance and also is liable to injure the edges of the cloth wound thereon.

It is also difficult to place printed matter on the ends of these boards and therefore it is an object of this invention to provide a foldable blank adapted to be slipped over each end of the bolt board and having a tongue whereby a gripping effect is obtained which prevents the end pieces from sliding off of the ends of the bolt board. Then the cloth is usually wound so that its edges overlap the caps which are placed over the ends of the bolt board to insure that they are held in position on the bolt board. Also this foldable blank, while in flat position lends itself easily to printing the trade-mark, name of manufacturer, type of goods, and the like on the end portions of the blanks which are then folded and inserted over the ends of the bolt board.

The board lends itself to speedy production in that the corrugated part is run on a regular corrugating machine, creased and then if desired taped on automatic tapers and both operations could be performed at one time, and in the same machine.

The end pieces lend themselves to mass production in that they can be printed a large number at a time upon a large sheet and then this sheet can be die cut to produce a plurality of the end pieces ready for folding to slip over the ends of the bolt board. Or, if desired, after the end pieces have been die cut and separated, they can be glued on automatic equipment. The bolt boards can be folded and as they come from the machine sidewise, an operator on each side can slip the caps or end pieces over the ends of the blank as it comes from the machine. Another advantage of these end pieces is the fact that ordinarily a label or wrap is glued at the ends which always presents an untidy appearance and whereby by the present invention, the appearance is uniform and clean looking.

Some of the objects of the invention having been stated, other objects will appear as the description proceeds when taken in connection with the accompanying drawings, in which

Figure 1 is an isometric view of a bolt board

2

and showing the end caps in assembled position and inserted over the ends of the bolt board;

Figure 2 is an isometric view of one of the end caps folded and glued together and ready for insertion over one end of the bolt board;

Figure 3 is a view similar to Figure 2 but showing the main flap in partly opened position and before it is completely folded ready for insertion over the bolt board as shown in Figure 2;

10 Figure 4 is a plan view of the blank before it is folded;

Figure 5 is an enlarged cross sectional view through the bolt board taken along the line 5—5 in Figure 1;

15 Figure 6 is a sectional view through one of the end pieces after it has been assembled, taken along the line 6—6 in Figure 2;

Figure 7 is an isometric view of a slightly modified form of bolt board but having the same end pieces fitted thereover;

20 Figure 8 is a cross sectional view taken along the line 8—8 in Figure 7;

Figure 9 is a cross sectional view taken along the line 9—9 in Figure 7;

25 Figure 10 is an edge of one of the bolt boards with cloth wound thereon and with the central portion thereof broken away.

Referring more specifically to the drawings, the numeral 10 indicates broadly a blank from 30 which the end pieces or caps for slipping over a cloth bolt board are formed. This blank comprises a main body portion 11 having crease lines 15 and 16 along which the blank is folded to form a first side wall 17.

35 Between the crease line 16 and the left-hand end of the blank in Figure 4 is a tab 18 which is adapted to occupy a horizontal position and in spaced relation to the portion 11. This tab can have adhesive applied to the lower side thereof

40 in Figure 4 or an adhesive 20 can be applied to the top side of a top portion 21 because the adhesive portion 20 and the end of the portion 18 are in overlapping position and adhesively secured together.

45 The top portion 21 is defined at one end by a crease line 23 and in spaced relation thereto is a crease line 24 forming a second side wall 25 similar to side wall 17.

50 The portion 21 has a gap 12 cut in the front edge thereof with slots 13 and 14 cut deeper inwardly and diagonally at the end of the gap 12.

The portions 17 and 25 have crease lines 27 and 28 forming tabs 29 and 30 which are adapted to be folded inwardly against the outer end of

55

the assembled member as is clearly shown in Figure 3.

There is a crease line 35 provided along which the material is bent to form an end wall 36. Hingedly connected to the end wall by a crease line 37 is top tab 38. This top tab 38 has cut away portions 39 and 40 near the ends thereof and has a transverse crease line 41 forming a turn-under tab 42 which is adapted to be turned in and abut against the cloth board to be presently described.

In assembling the blank to form the finished unit as shown in Figures 1 and 2, the material is bent along the crease lines 15, 16, 24 and 23 and the ends of tab 18 and top 21 are over-lapped and adhesively secured together. Then the tabs 29 and 30 are folded inwardly and then the material is bent upwardly along the crease line 35 to form an end wall 36 fitting against the end of the cloth board, and then the material is creased along the crease line 31 to form the top tab 38 which extends upwardly and over the top of the assembled unit. The restricted portion occurring between cut away portions 39 and 40 is fitted into the gap 12 and the edges thereof are slipped into the diagonal slots 13 and 14 and the tab 42 is turned underneath the front edge of the gap 12 and exerts a gripping effect on the end of the cloth board to prevent its accidental removal once it is installed in position.

A cloth board is usually made from corrugated paper and can be in either of the form shown in Figures 1 and 5 or of the form shown in Figures 7, 8 and 9. When it is formed from the type of light stock board shown in Figures 1 and 5 it is indicated broadly by reference character 50 and has a bottom portion 51 which is bent at points 52 and 53 and is directed upwardly and bent at points 54 and 55 and then is again bent at points 56, 57, 58 and 59, then when firmly pressed in this position, will remain in this position, without any adhesive or the like, because the units slipped over each end thereof will hold it in assembled position. This forms a three layer board comprising the main layer 51 and half width layers 45, 46, 47 and 48.

This type of board can be made of heavier stock as shown in Figures 7, 8, and 9. In Figures 7, 8 and 9 the structure comprises a main base portion 60 bent at each end as at 61, 62, 63 and 64 providing upper half portions 65 and 66 which can, if desired, be adhesively secured in position by means of a strip of gummed paper 67.

In either event when the cloth boards are assembled the end or cap members formed from the blanks 10 are slipped over the ends of the board and then the assembly is ready for the winding of cloth thereon.

This cloth is usually wound thereon and is indicated at 70 and partially covers the end pieces or caps which are slipped over the ends of the cloth board before the cloth is wound thereon and thus the cloth holds the end pieces or caps in position over the ends of the cloth board and prevents their accidental loss therefrom.

In the drawings and specification there has

been set forth a preferred embodiment of the invention, and although specific terms are employed, they are used in a generic and descriptive sense only, and not for purposes of limitation, the scope of the invention being defined in the claim:

We claim:

A single blank cap member adapted to be fitted over the end of a rectangular cloth board comprising a main body portion, first and second side walls hingedly connected to the ends of the main body portion, a tab hingedly connected to the other side of the first side wall, a top portion hingedly connected to the other edge of the second side wall, an end wall hingedly connected to the one side edge of the main body portion, a top tab hingedly connected to the other edge of the end wall, the top tab diminishing in width as it extends from its point of connection with the end wall, the free end of the top tab having a turn under tab hingedly connected thereto, the first and second side walls each having a tab hingedly secured to the ends thereof which are adjacent the end wall, the top portion having an extended gap cut in the front edge thereof and having diverging slots cut therein at the ends of the gap, the side walls being folded to right angular position with relation to the main body portion and the tab secured to the first side wall and the top portion being folded to overlapping relation and parallel to the main body portion and secured to each other, the tabs secured to the side walls being folded towards each other, the end wall being folded upwardly against the last-named tabs, the top tab being folded onto the top of the top portion, the restricted portion of the top tab being folded into said gap and having its side edges fitting into said diverging slots and the turn under tab being folded beneath the front edge of the top portion to hold the parts in assembled position.
